UNITED STATES PATENT OFFICE

WILLIAM J. DE WITT, OF AUBURN, NEW YORK, ASSIGNOR TO SHOE FORM CO., INC.,
OF AUBURN, NEW YORK, A CORPORATION OF NEW YORK

SHOE FORM

Application filed April 16, 1931. Serial No. 530,515.

This invention relates to an improvement in shoe forms and more particularly in expandable toe forms adapted to be inserted into the toe of a shoe and expanded therein to plump out the shoe and put it in the ideal condition for display or other purposes.

Various types of such toe forms have been proposed and suggested heretofore and the object of the present invention is to provide an improvement upon the means for expanding and contracting the toe form such improvement including a crossbrace made into two sections pivotally connected to function and a toggle and having means for positively 15 limiting the expansion and contraction of the form thereby avoiding the possibility of placing excessive pressure against the shoe when the form is expanded and preventing any undue contraction of the form when it is 20 being inserted into or withdrawn from the shoe.

Other objects of the invention reside in the provision of the particular structural features set forth in the following description and illustrated in the accompanying drawings wherein

Fig. 1 is a side elevation of a toe form embodying this invention;

Fig. 2 is a bottom plan view of the toe form 30 shown in Fig. 1 in the expanded position;

Fig. 3 is a view similar to Fig. 2 the form being in the contracted position;

Figs. 4 and 5 are enlarged cross sectional views taken along the line 4—4 of Fig. 2 and 35 the line 5—5 of Fig. 3 respectively;

Figs. 6 and 7 are views corresponding to Figs. 2 and 3 respectively of another embodiment of this invention; and

Figs. 8, 9 and 10 are enlarged cross sectional views taken along the line 8—8 of Fig. 6 and the lines 9—9 and 10—10 of Fig. 7 respectively.

The two embodiments here illustrated differ from each other merely by reason of the structure of the crossbraces by which the side walls are connected, each embodiment comprising a body portion 10 having side walls 11 and 12 which terminate in flanges 13 and 14.

The side walls of the embodiment shown

in Figs. 2 to 5 inclusive are connected by a crossbrace 15 of the toggle type and consisting of bars 16 and 17. The bar 16 is pivotally secured at one end to the flange 13 of the side wall 11 as by a rivet 18 and the bar 17 is similarly secured at one end to the flange 14 of the side wall 12 as by a rivet 19. The other ends of the bars are pivotally connected as by a rivet 20 to which one end of a retractor 21 is secured. This retractor is here shown as a wire 22 enclosed in a tube 23 of celluloid.

The free end of the bar 17 is rounded to form a shoulder 25 and the bar 16 has intermediate its ends a transversely extending ledge 26 with which the shoulder 25 contacts to define the expanded position of the form (see Figs. 2 and 4) and the contracted position thereof (see Figs. 3 and 5). The bars 16 and 17 are preferably of celluloid which 70 may be laminated as shown in Figs. 4 and 5. The shoulder 25 is formed on the upper lamina 30 which projects beyond the lower lamina 31 while the ledge 26 is formed by the lower lamina 32 which stops short of the upper 75 lamina 33. The rivet 20 extends through the upper laminae 30 and 33. Other ways of forming the shoulder 25 and the ledge 26 and of joining the bars may of course be employed, those herein described having been selected for the purpose of illustration and not limitation.

It will be apparent that when the retractor 21 is pulled to the left in Fig. 1 the form is contracted as in Fig. 3 until the portion 27 of the shoulder 25 contacts with the ledge 26. The form is now in condition to be inserted into or withdrawn from the toe of a shoe. After being inserted in a shoe the form is expanded by pushing the retractor 21 to the right in Fig. 1 until the form takes the expanded position illustrated in Fig. 2 with the portion 28 of the shoulder in contact with the ledge 26.

Since the embodiment shown in Figs. 6 to 10 inclusive differs from that previously described only in the form of crossbrace employed primed reference characters corresponding to those used above have been ap- 100

plied to the common elements and no description thereof is believed necessary.

The bars 16' and 17' forming the cross-brace 15' as shown in detail in Figs. 8, 9 and 5 10 are also of laminated celluloid. Mounted upon the lower lamina 32' of the bar 16' is a lamina 40 while a similar lamina 41 is mounted upon the lower lamina 31' of the bar 17'. These laminae 40 and 41 are hereinafter 10 referred to as shoulders and as shown in Figs. 6 and 8, contact with the edges of the side wall flanges 13' and 14' respectively to define the expanded position of the form.

When the form is contracted the shoulder 15 41 contacts with the edge of the flange 14' to define the contracted position. The lamina 30' of the bar 17' may contact with the lamina 32' of the bar 16' as shown in Fig. 10 to further define this position.

20 The operation of this embodiment is substantially that of the first embodiment and is apparent from the above description. It accordingly will not be set forth in detail.

While two embodiments of the invention 25 have been shown and described I am not limited thereto since other embodiments can be made without departing from the spirit and scope of the invention as set forth in the following claims.

30 I claim:

1. An expandible toe form comprising a hollow body portion and a crossbrace of the toggle type connecting the side walls of the body portion, the crossbrace comprising two 35 bars, each pivotally connected at one end to one of said side walls and pivotally connected together at the other ends, said bars being movable relative to each other by application of pressure at the joined ends thereof, between two positions, in one of which the side 40 walls are expanded and in the other of which the side walls are contracted, and means carried by one of said bars which engages the other bar and defines the position in which the side walls are contracted.

2. An expandible toe form comprising a hollow body portion and a crossbrace of the toggle type connecting the side walls of the body portion, the crossbrace comprising two 50 bars, each pivotally connected at one end to one of said side walls and pivotally connected together at the other ends, said bars being movable relative to each other by application of pressure at the joined ends thereof, between two positions, in one of which the side 55 walls are expanded and in the other of which the side walls are contracted, and a shoulder on one of said bars with which the other bar engages to define the position in which the side walls are contracted.

3. An expandible toe form comprising a hollow body portion and a crossbrace of the toggle type connecting the side walls of the body portion, the crossbrace comprising two 60 bars, each pivotally connected at one end to

one of said side walls and pivotally connected together at the other ends, said bars being movable relative to each other by application of pressure at the joined ends thereof, between two positions, in one of which the side 70 walls are expanded and in the other of which the side walls are contracted, and a shoulder on one of said bars with which the other bar engages to define both of said positions.

4. An expandible toe form comprising a 75 hollow body portion and a crossbrace of the toggle type connecting the side walls of the body portion, the crossbrace comprising two bars, each pivotally connected at one end to one of said side walls and pivotally connected together at the other ends, said bars being movable relative to each other by application of pressure at the joined ends thereof, between two positions, in one of which the side 80 walls are expanded and in the other of which the side walls are contracted, and a shoulder on one of said bars which engages with the side wall to which the bar is pivoted to define the position in which the side walls are contracted.

5. An expandible toe form comprising a hollow body portion and a crossbrace of the toggle type connecting the side walls of the body portion, the crossbrace comprising two bars, each pivotally connected at one end to one of said side walls and pivotally connected together at the other ends, said bars being movable relative to each other by application of pressure at the joined ends thereof, between two positions, in one of which the side 90 walls are expanded and in the other of which the side walls are contracted, and a shoulder on one of said bars which engages with the side wall to which the bar is pivoted to define the position in which the side walls are contracted.

5 tween two positions, in one of which the side walls are expanded and in the other of which the side walls are contracted, and a shoulder on each of said bars which engages with the side wall to which the bar is pivoted to define one of said positions.

10 8. An expandible toe form comprising a hollow body portion and a crossbrace of the toggle type connecting the side walls of the body portion, the crossbrace comprising two bars, each pivotally connected at one end to one of said side walls and pivotally connected together at the other ends, said bars being movable relative to each other by application 15 of pressure at the joined ends thereof, between two positions, in one of which the side walls are expanded and in the other of which the side walls are contracted, and a shoulder on each of said bars which engages with the side wall to which the bar is pivoted to define 20 the position in which the side walls are expanded.

25 9. An expandible toe form comprising a hollow body portion and a crossbrace of the toggle type connecting the side walls of the body portion, the crossbrace comprising two bars, each pivotally connected at one end to one of said side walls and pivotally connected together at the other ends, said bars being 30 movable relative to each other by application of pressure at the joined ends thereof, between two positions, in one of which the side walls are expanded and in the other of which the side walls are contracted, and a shoulder on one of said bars which defines both of said 35 positions.

Signed by me at Auburn, New York, this
14th day of April, 1931.

40 WILLIAM J. DE WITT.
